UNITED STATES PATENT OFFICE

LOWELL J. SMITH, OF CONNERSVILLE, INDIANA, ASSIGNOR TO STANT MANUFACTURING CO., OF CONNERSVILLE, INDIANA, A CORPORATION OF INDIANA

DESIGN FOR A COMBINED PAPER WEIGHT AND PEN HOLDER

Application filed February 11, 1933. Serial No. 47,192. Term of patent 7 years.

To all whom it may concern:

Be it known that LOWELL J. SMITH, a citizen of the United States, residing at Connerville, in the county of Fayette and State of Indiana, has invented a new, original, and ornamental Design for a combined Paper Weight and Pen Holder, of which the following is a specification, reference being had therein to the accompanying drawing, forming part thereof, in which—

The figure in the drawing is a perspective view of a combined paper weight and pen holder showing my new design.

I claim:

The ornamental design for a combined paper weight and pen holder as shown.

In testimony whereof, I affix my signature.

LOWELL J. SMITH.
